(57) **CLAIM**

The ornamental design for a crop furrow, as shown and described.

DESCRIPTION

FIG. 1 is a cross sectional view of the crop furrow taken from line 1-1 in FIG. 2;

FIG. 2 is a perspective view of the crop furrow; FIG. 3 shows an exploded view of FIG. 2 showing a top cover, a supporting frame, an irrigation pipe, a lighting system, and a ground cover on shaped cavity in ground soil; FIG. 4 is an environmental perspective view of the crop furrow;

FIG. 5 is a top view of the top cover; the bottom view is a copy of the top view;

FIG. 6 is a front view of the top cover, and the rear view of the top cover is a copy of the front view;

FIG. 7 is a right edge view of the top cover, the left edge view is a mirror image thereof;

FIG. 8 is perspective view of the top cover;

FIG. 9 is a front view of the supporting frame;

FIG. 10 is a top view of the supporting frame;

FIG. 11 is a bottom view of the supporting frame;

FIG. 12 is a right side view of the supporting frame;

FIG. 13 is a left side view of the supporting frame;

FIG. 14 is a perspective view of the supporting frame;

FIG. 15 is a front view of the irrigation pipe with a riser; the back side view is a mirror image of the front view; the underside of the irrigation pipe has no ornamentation;

FIG. 16 is a right side view of the irrigation pipe and riser, the left side view is a mirror image of the right side view;

FIG. 17 is a perspective view of the irrigation pipe and riser;

FIG. 18 is a front view of the lighting;

FIG. 19 is a right side view of the lighting; the left side view is a mirror of the right side view;

FIG. 20 is a top view of the lighting;

FIG. 21 is a bottom view of the lighting;

FIG. 22 is a back view of FIG. 18;

FIG. 23 is a perspective view of the lighting;

FIG. 24 is a front view of the ground cover; the back view is a copy of the front view;

FIG. 25 is a right side view of the ground cover, the left side view is a mirror of the right side view;

FIG. 26 is a top view of the ground cover;

FIG. 27 is a bottom view of the ground cover;

FIG. 28 is a perspective view of the ground cover; and,

FIG. 29 is a detailed view of FIG. 17.

The dash dot lines in FIGS. 2-8, 15-28 represent boundaries of the claim and form no part of the claimed design. The dashed lines in FIGS. 1-3, 15-24, 26-29 represent environment and form no part of the claimed design. The dash

(Continued)

double dot line in FIG. 17 indicates a detailed view and forms no part of the claimed design.
